AUXILIARY DOOR OPERATING MECHANISM

David C. E. Leonard, Hagerstown, Md., assignor
to Jamison Cold Storage Door Company,
Hagerstown, Md., a corporation of Maryland

Application April 12, 1939, Serial No. 267,486

8 Claims. (Cl. 268—14)

The present invention relates to new and useful improvements in a multiple door system including main and auxiliary doors, and more particularly to the provision of operating means for effecting operation of an auxiliary door in conjunction with the main door.

A multiple door system including main and auxiliary doors may be employed in various instances, as for instance, in plants requiring relatively large refrigerator or cold storage chambers. Thus, the present invention is particularly concerned with the provision of a refrigerator door system which includes a main refrigerator door and an auxiliary track door. It is customary to provide a main opening which is controlled by the main refrigerator door, and an auxiliary opening through which a track extends. An auxiliary door is employed for controlling the opening through which the track extends. The articles to be placed in the refrigerating chamber are customarily supported from carriages of any suitable type. These carriages or hangers generally consist of a depending bracket and a wheel which travels along the track and by which the carriages or hangers are supported. The track opening communicates with the large opening and the articles hang from the carriages travelling on the track so that they may pass through the main opening while the carriages pass along the track through the track opening. The present invention is concerned, therefore, with the provision of a door system including a main door for closing the main opening below the track and an auxiliary door for closing the opening through which the track extends.

An object of the invention is to provide a multiple door system of the above type, wherein the auxiliary door is opened or closed in conjunction with the opening or closing of the main door by an operating mechanism which effects full opening of the auxiliary door during the initial opening movement of the main door and which effects closing of the auxiliary door only during the latter part of the closing movement of the main door.

A still further object of the invention is to provide a door operating mechanism of the above type, wherein a cam member is movable with the main door and cooperates with a linkage or lever system for effecting full opening of the auxiliary door during the initial opening movement of the main door, and wherein the cam member becomes disengaged from the linkage or lever system during further opening of the main door so that closing of the auxiliary door is de-

layed until the latter part of the closing movement of the main door.

A still further object of the invention is to provide a door operating mechanism of the above type, wherein the cam member on the main door is in the form of a bracket which is shaped so that it may be interchangeably used on the right or left hand sides of the main door, depending upon the side thereof which is hinged to the door frame.

The invention still further aims to provide a door operating mechanism of the above type which is of a relatively simple construction, which is easily assembled, and which is thoroughly efficient in use.

The above and other objects of the invention will in part be obvious and will be hereinafter more fully pointed out.

In the accompanying drawings,

Figure 1 is a fragmentary side view, in section, showing in full lines the portions of the door operating mechanism with the main and auxiliary doors closed, and showing in dotted lines the portions of the door operating mechanism with the auxiliary door fully opened and the main door partially opened.

Figure 2 is a reduced top view, in section, showing the main door closed and omitting the auxiliary door and the upper link.

Figure 3 is a view similar to Figure 2, but showing the main door in a partially opened position.

Referring more in detail to the accompanying drawings, the refrigerating chamber includes a front wall 10, a portion of which is inset, as at 11, to provide a frame and a relatively large opening into the refrigerator chamber. This opening is adapted to be closed by a main refrigerator door D. There is provided a smaller opening above the large opening and communicating therewith. The top of the small opening is defined by a wall section 12 and the vertical sides thereof are defined by wall sections 13, 13a. A conveying track T extends from any desired point outside the refrigerating chamber through the small opening to the interior of the refrigerating chamber and this small opening is adapted to be closed by an auxiliary track door D'. The track T may be supported in any suitable manner and carriages or hangers (not shown) are adapted to travel on the track. When the doors D, D' are open, a carriage is adapted to pass along the track through the small opening and the article hanging from the carriage is

adapted to pass through the large opening therebelow.

The main refrigerator door includes a front panel 14, and a rear panel 15, these panels being separated by suitable laterally extending portions 16 and the interior of the door may be filled with a suitable insulating material. The peripheral edges of the front panel 14 extend beyond the lateral portions 16 to define a peripheral flange 14a to which is secured a sealing gasket 17. The main door D is pivotally connected along one vertical edge thereof to the front wall 10 of the refrigerating chamber by means of hinges 18. Thus, the main door D is adapted to swing about a vertical axis.

The auxiliary track door D' is connected to the front wall 10 of the refrigerating chamber by means of a horizontally extending hinge 19. The track door depends from the hinge 19 and has a vertical slot 20 through which the track T extends when the auxiliary door is closed. A suitable sealing gasket 21 is provided on the auxiliary door D' for cooperation with the front wall of the refrigerating chamber to seal the interior thereof. The track door may also be provided with a flexible sealing curtain which cooperates with the top edge of the main door D for sealing the interior of the refrigerating chamber.

A bracket member B includes a supporting base 23 which is secured by screws 24 or the like to the top horizontal edge 16 of the main door D. This bracket is secured to the main door adjacent the edge of the small opening which is nearest the hinge mounting for the main door. The screws 24 pass through slots 25 in the supporting base, these slots permitting adjustment of the bracket member. The bracket member B includes a vertically disposed substantially U-shaped rib 26 which defines arm portions extending substantially parallel to one another toward the outside of the refrigerating chamber and toward the auxiliary door when both doors are closed. The arms of the rib 26 are both provided with laterally extending flanges 27, 28, these flanges extending on opposite sides of the rib and being symmetrical. At the free ends of the arms of the rib 26, the flange 27 extends upwardly, as at 29, and the flange 28 extends upwardly, as at 30. Both flanges 27, 28 are provided with relatively wide portions 31, 32, respectively, at the rear ends thereof. These flanges gradually taper outwardly on both sides of the rib 26 from a point substantially in line with the point at which the base 23 is secured to the main door. Both flanges 27, 28 are inclined with respect to a horizontal plane and are substantially parallel to one another. However, the rear end of the flange 27 is disposed in a substantially horizontal plane so as to provide a larger space between the rear ends of both flanges.

A bracket B' is secured to the auxiliary door near the edge of the small opening which is adjacent the hinged connection for the main door. The bracket B' includes a pair of apertured ears 33 between which one apertured end of a link 34 is pivotally mounted by means of a pin 35. The opposite apertured end of the link 34 is adapted to be pivotally connected to a lever 36. A plate 37 is secured by screws 38 or the like to the side of the small opening adjacent the bracket B'. The lower end of the lever 36 is pivotally connected by means of a pin 38 adjacent the bottom end at the forward edge of the plate 37. The upper end of the lever 36 is shaped to provide a re-

cess defined by offset side portions 39, 39a which are apertured and between which the free end of the link 34 is adapted to extend. A pin 40 extends through the side portions 39, 39a and the apertured end of the link 34 to provide the pivotal connection. An adjustable screw 41 passes through the upper end of the lever 36 and extends into the recess provided between the offset plate portions 39, 39a. The screw serves as a stop in the manner hereinafter pointed out.

A roller 42 is secured to the lower end of the lever 36 adjacent the pivot pin 38 and extends outwardly therefrom. This roller is of such a size that it fits closely between the flanges 27, 28 on the bracket member B. In the full line position shown in Figure 1, the roller 42 is disposed in contact with the upwardly extending end 30 of the flange 28 so that tight closing of the main door D will tend to urge the lever 36 in a counterclockwise direction, thus tending to tightly close the track door D' by means of the link 34 which is connected to the upper end of the lever 36.

In operation, initial opening movement of the main door D will effect corresponding movement of the bracket member B which is carried thereby. This movement of the bracket member B will cause the roller 42 on the lever 36 to abut against the downwardly and inwardly inclined flange 27 so as to effect clockwise movement of the lever 36 about the pivot pin 38. This movement of the lever 36 will effect outward movement of the link 34 and the auxiliary track door D'. During this initial opening movement of the main door D, the flange 27 tends to leave the roller 42, but the wide rear portion 31 of this flange still remains in contact with the roller 42 so as to effect a full opening of the auxiliary door D' before the bracket B completely leaves the roller 42. Thus, when the main door leaves the position of Figure 3, full opening movement of the auxiliary door is effected by contact of the wide portion 31 of the flange 27 with the roller 42. Further opening movement of the main door disengages the bracket B from the roller 42. In the full open position of the auxiliary door D', the link 34 and the lever 36, which constitute a toggle connection, pass dead center, as shown in dotted lines in Figure 1, so that the end of the stop screw 41 will abut against an adjacent portion of the link 34, thus constituting a stop for maintaining the auxiliary door in its full open position.

In closing the main door D, the roller 42 on the lever 36 does not become engaged between the flanges on the bracket B until the latter part of this closing movement. The rear ends of the wide portions 31, 32 of the flanges 27, 28, respectively, are spaced apart a slightly wider distance so as to assure that the roller 42 will be engaged thereby. When the roller becomes positioned between the enlarged portions 31, 32 of the flanges, the roller will bear against the lower flange 28 so that final closing movement of the main door will effect counterclockwise movement of the lever 36 about its pivot 38. Thus, the locked position between the link 34 and the lever 36 will be broken and the auxiliary door D' will be controlled during its closing movement by engagement of the roller 42 between the flanges 27, 28. In a fully closed position, the upwardly extending end 30 on the flange 28 will engage the roller 42 and tend to tightly close the auxiliary door as the main door is tightly closed.

From the foregoing description, it will be readily seen that the upper and lower flanges 27, 28, respectively, on the bracket member B provide

spaced and substantially parallel camming members or surfaces between which the roller 42 on the lever 36 is disposed during opening or closing of the auxiliary track door D'. The flanges 5 27, 28 extend laterally on both sides of the rib 26 on the bracket member B so that this bracket member can be employed on either side of the track opening, depending upon the position of the hinge for the main door D. The relatively 10 wide portion 31 of the flange 27 serves to maintain engagement with the roller 42 until the auxiliary track door is fully opened. Then, the roller becomes disengaged from the flange during full opening of the main door. Upon closing of 15 the main door, the roller 42 does not become engaged between the flange on the bracket B until the latter part of the closing movement of the main door. During the latter part of this closing movement, the roller engages the relatively wide 20 portion 32 on the flange 28 so as to break the locking position of the link 34 and the lever 36. Thereafter, the roller remains engaged between the flanges 27, 28, so that closing movement of the auxiliary door is controlled and is operated 25 in synchronism with the final closing of the main door. Thus, the initial opening of the main door effects full opening of the auxiliary door while closing of the auxiliary door is not effected until the final closing movement of the 30 main door.

While one form of the invention has been shown in the accompanying drawings for purposes of illustration, it is to be clearly understood that various changes in the details of construction and arrangement of parts may be made without departing from the scope of the invention as set forth in the appended claims.

I claim:

1. In a multiple door system having main and auxiliary doors, an operating mechanism for the auxiliary door comprising a link having one end thereof pivotally connected to the auxiliary door, a lever having one end thereof pivotally connected to the door frame and having the opposite end thereof pivotally connected to the opposite end of said link, a bracket member carried by the main door and including cam members extending laterally therefrom and increasing in width toward the rear ends thereof, and means on said lever engageable with said cam members for effecting opening and closing of the auxiliary door upon opening and closing of the main door.
2. In a multiple door system having main and auxiliary doors, an operating mechanism for the auxiliary door comprising a link having one end thereof pivotally connected to the auxiliary door, a lever having one end thereof pivotally connected to the door frame and having the opposite end thereof pivotally connected to the opposite end of said link, a bracket member carried by the main door and including a pair of spaced arms having substantially parallel cam surfaces extending laterally on each side of said bracket member whereby the bracket member may be fixed to the main door at either side of an opening, and a member extending laterally from said lever and engageable with said cam surfaces for effecting opening and closing of the auxiliary door upon opening and closing of the main door.
3. In a multiple door system having main and auxiliary doors, an operating mechanism for the auxiliary door comprising a link having one end thereof pivotally connected to the auxiliary door, a lever having one end thereof pivotally con-

nected to the door frame and having the opposite end thereof pivotally connected to the opposite end of said link, a bracket member carried by the main door and having a pair of arms providing a U-shaped slot opening outwardly toward the auxiliary door when closed, said arms having spaced substantially parallel cam surfaces, and a roller extending laterally from said lever and adapted to extend into the U-shaped slot for engagement with said cam surfaces whereby 10 to effect opening and closing of the auxiliary door upon opening and closing of the main door.

4. In a multiple door system having main and auxiliary doors, an operating mechanism for the auxiliary door comprising a link having one end thereof pivotally connected to the auxiliary door, a lever having one end thereof pivotally connected to the door frame and having the opposite end thereof pivotally connected to the opposite end of said link, a bracket member carried by the 20 main door and including spaced cam surfaces extending laterally on each side of said bracket member whereby the bracket member may be fixed to the main door at either side of an opening, and means on said lever engageable with 25 said cam surfaces for effecting opening and closing of the auxiliary door upon opening and closing of the main door.

5. In a multiple door system having main and auxiliary doors, an operating mechanism for the 30 auxiliary door comprising a link having one end thereof pivotally connected to the auxiliary door, a lever having one end thereof pivotally connected to the door frame and having a recess at the opposite end thereof for receiving the opposite end of said link, means providing a pivotal connection between the recessed end of said lever and the opposite end of said link, a bracket member carried by the main door and including cam members 35 extending laterally on each side of said bracket member whereby the bracket member may be fixed to the main door at either side of an opening, and means on said lever engageable with said cam members for effecting opening and 40 closing of the auxiliary door upon opening and 45 closing of the main door.

6. In a multiple door system having main and auxiliary doors, an operating mechanism for the auxiliary door comprising a link having one end thereof pivotally connected to the auxiliary door, 50 a lever having one end thereof pivotally connected to the door frame and having the opposite end thereof pivotally connected to the opposite end of said link, a bracket member carried by the main door and including a vertically disposed 55 rib portion providing spaced parallel arms, flanges extending laterally on each side of said arms and providing cam surfaces, and means on said lever engageable with said cam surfaces for effecting opening and closing of the auxiliary 60 door upon opening and closing of the main door.

7. In a multiple door system having main and auxiliary doors, an operating mechanism for the auxiliary door comprising a link having one end thereof pivotally connected to the auxiliary door, 65 a lever having one end thereof pivotally connected to the door frame and having the opposite end thereof pivotally connected to the opposite end of the link, a bracket member carried by the main door and including upper and 70 lower cam surfaces, a roller on said lever engageable with said cam surfaces for effecting opening and closing of the auxiliary door upon opening and closing of the main door, said lower cam surface having an upwardly extending end 75

- portion engageable with said roller when the main door is closed for effecting a tight closing of the auxiliary door.
8. In a multiple door system having main and auxiliary doors, an operating mechanism for the auxiliary door comprising a link having one end thereof pivotally connected to the auxiliary door, a lever having one end thereof pivotally connected to the door frame and having the opposite end thereof pivotally connected to the opposite end of said link, a bracket member carried by the main door and having a pair of arms providing
- 5 a U-shaped slot opening outwardly toward the auxiliary door when closed, said arms having spaced substantially parallel cam surfaces extending laterally from said arms and gradually increasing in width toward the rear ends thereof, and a roller extending laterally from said lever and adapted to extend into the U-shaped slot for engagement with the cam surfaces whereby to effect opening and closing of the auxiliary door upon opening and closing of the main door. 10

DAVID C. E. LEONARD.
